HIDAWAE PRODUCTS CORPORATION, OF MIAMI, FLORIDA, A CORPORATION OF
FLORIDA

WINDOW AND DOOR

Application filed September 7, 1928. Serial No. 304,496.

This invention relates to windows and doors of buildings, and has for its principal object a closure for such openings so constructed of a plurality of units that the whole 5 or any part of the window or door may be opened so as to provide the maximum amount of opening, without the use of complicated, cumbersome or unsightly parts.

With this object in view, the invention consists of the arrangement of the window or door units having a novel construction of rails so that the upward movement of the lowermost unit will be successively communicated to the upper units and finally carried thereby 15 into a pocket or housing above the window or door casing to provide a 100 per cent opening and so that the downward movement of the lowermost unit from a raised position will be successively communicated to the raised 20 upper units to completely close the window or door.

The invention further consists of the novel arrangement and combination of parts, all of which will be first fully described and 25 afterwards specifically pointed out in the appended claim.

Referring to the accompanying drawings:

Figure 1 is a perspective view of a house illustrating the improved windows in the 30 several positions of fully closed, half open and fully open.

Figure 2 is a transverse horizontal sectional view taken on line 2—2 of Figure 1.

Figure 3 is a view of the window partly in 35 elevation and partly in vertical section.

Figure 4 is a vertical sectional view taken on line 4—4 of Figure 3.

Figure 5 is a similar view illustrating the 40 units of the window in full raised position.

Figure 6 is an enlarged fragmentary perspective view of the two lowermost units illustrating the construction of the lower rails of the sash units and

Figure 7 is a perspective view of a form of 45 operating crank and lock.

Like numerals of reference indicate the same parts throughout the several figures, in which:

50 1 indicates the improved window and 2

indicates the sash units, which in the style of window illustrated in the drawings is composed of four units. It is to be clearly understood however, that the number of units employed is entirely a matter of choice or convenience, and is largely dependent upon the size of the window or door and the architecture of the building. It is also to be clearly understood that while the drawings illustrate our invention as applied to windows, the improved construction is equally applicable to doors, as will be evident without additional illustration.

3 indicates the window frame, the sides 4 of which are provided with a groove 5 for 55 each sash unit 2, and a bead 6 separating each groove.

7 indicates the window sill, which as shown in Figure 4 may be provided with a depending flange 8 to prevent the entrance of water 60 from the outside under the sill.

The entire structure may be made of metal or of wood, or partly of metal and partly of wood, as may be desired.

9 indicates the top trim of the window, 75 the window opening extending of course from the sill 7 to the top trim 9. Above the trim 9 is a chamber or pocket 10 into which the side frames 4 of the window extend and which are joined together at their tops by a 80 cross-frame 11.

Referring now to the sash units 2, it will be seen that we prefer to equip each unit with a pair of rollers 12 in each side edge of the sash units to facilitate the easy movement of 85 the same in the sash grooves 5 of the side frame 4.

The lowermost sash unit 2 has a bottom rail 13 provided with a small outwardly extending flange 14, (Figures 4 and 6) while the top rail 15 of said unit 2 has a similarly outwardly extending flange 16. The lower rail 17 of the next sash unit 2 has a small inwardly projecting flange 18 arranged in the path of movement of the flange 14 of the 90 lower rail 13, and also has a small outwardly extending flange 19.

The lower rail 17 of the next or third sash unit is also provided with said inwardly and outwardly extending flanges 18 and 19, while 100

the lower rail 17 of the top unit 2 is also equipped with said flanges 18 and 19.

The upper rails 15 of the second and third sash units 2 are equipped with small outwardly extending flanges 16 and are identical with the upper rail 15 of the lowermost sash unit so that all of said outwardly extending flanges 16 are disposed in the path of movement of the adjacent inwardly extending flanges 18 on the lower rails of the sash units.

A variation however, exists as to the upper rail of the top sash unit 2, inasmuch as a cap 20 is fixed on said rail which provides a slight outward extension 21' to engage on top of a bead or flange 22'' at the bottom of the chamber or pocket 10. The size of the cap 20 is such as to completely close off the said chamber or pocket 10 when the sash units 2 are in a lowered position as shown in Figures 3 and 4, in order to provide a finish to the window construction. But said cap 20 is raised up into the top of the chamber or pocket 10 when the sash units 2 are in fully raised position as shown in Figure 5. In this position, the bottom rails of all of the sash units close the chamber or pocket 10 as shown in said figure.

It may be found convenient to supply some suitable means for raising the sash units 2, other than by sliding the sash units by hand, and such raising can be accomplished in any suitable manner. It is also entirely obvious that the size, style, and type of the window or door will determine the character of the construction of the raising or operating mechanism, and that therefore the raising or operating mechanism would of course be changed or varied to meet the conditions as they are found to exist.

It will be seen from Figures 3, 4 and 5 that we may employ a removable section 4' in one of the sides 4 of the groove 3. When this section 4' which is also provided with grooves and beads 5 and 6, the sash units 2 may be quickly inserted in or removed from the frame. Screws 3', as shown in Figure 4 retain the removable section 4' in operative position shown in said figure.

Simply for the purpose of illustrating a raising or operating mechanism, but not for the purpose of limiting the invention to such construction, we have shown in the drawings an embodiment which consists of a pair of sprocket wheels 21 at the top and bottom of the structure over which run chains 22 having their ends secured to the corners of the lowermost sash section 2, in such manner as to lie within the groove 5 for said sash unit as shown in dotted lines on the left side of Figure 3. A shaft 22' (Figure 7) may carry one of the lower sprockets 21, and may also carry a similar sprocket 23 which may be connected by a chain 24 to a similar sprocket on the opposite side of the window structure. A crank 24' having a slidable handle 25 car-

rying a slidable pin 26, may be mounted on the crank 24', while an escutcheon plate 27 having therein a hole 28 to receive said slideable pin 26 may be mounted at the bottom of the window structure as shown in Figure 3. By this construction, the sash units may be raised or lowered and also locked in a raised, lowered or intermediate position, by the slideable pin 26 entering the hole 28 in the plate 27.

Any other suitable operative or locking device may be employed without departing from the spirit of our invention.

Having thus described the several parts of the invention, it is believed that the operation of the same will be obvious from an inspection of the accompanying drawings taken in connection with the foregoing specification.

However, it may be said that upon upward movement of the lowermost sash unit 2 the flange 14 on its lower rail 13 engages the inwardly extending flange 18 on the lower rail 17 of the second sash unit 2, and raises said second sash. As the upward movement is continued, the outwardly extending flange 19 on the lower rail 17 of the second sash unit, engages the inwardly extending flange 18 on the lower rail 17 of the third sash unit and raises said third sash unit. As this upward movement progresses, the outwardly extending flange 19 on the lower rail 17 of the third sash unit engages the inwardly extending flange 18 on the lower rail 17 of the fourth or uppermost sash unit, and raises said fourth sash unit so that all of the sash units are finally raised and housed in the chamber or pocket 10, as shown in Figure 5.

At any point during this upward progress of the sash units, the slideable pin 26 may be dropped into the hole 28 in the plate 27 and the window sash units locked in any intermediate or partially raised position or in fully raised position, as shown in Figure 5.

To lower the sash units, the outwardly projecting flanges 16 on the top rails 15 of the sash units successively engage the inwardly projecting flanges 18 on the lower rails 17 of the sash sections to close the window as shown in Figure 4. These outwardly extending flanges 16 on the top rails 15 of the sash units also prevent independent upward movement of the second, third and fourth sash units and thus retain these sash units against opening or movement from the outside, when the lowermost sash unit is locked in its lowered position as shown in Figure 4.

Having thus described the invention, it will be seen that the objects of the invention are accomplished by a simple and an inexpensive construction. And while we have shown only a single embodiment of the same, we are fully aware that various changes and alterations may be made therein without departing from the spirit of the invention, and we consider ourselves clearly entitled to all

such changes and modifications, as fall within the limit and scope of the appended claim.

What we claim as new and desire to secure by Letters Patent of the United States is:

5 A device of the character described including a frame having sides provided with grooves and beads, a plurality of units slideable in said grooves, each unit including an upper rail and a lower rail, the lowermost
10 rail of each unit being provided with an outwardly extending flange, and the lowermost rail of certain of the units being provided with an inwardly extending flange disposed in the paths of upward movement of the outwardly extending flanges of the adjacent units, the upper rail of certain of the units being provided with an outwardly extending flange arranged above the said inwardly extending flange on the lower rail of its adjacent unit and in the path of downward movement thereof, the device being provided at its top with a pocket to receive and house all of the units, a cap mounted on and movable with the upper rail of the top unit to completely close off the said pocket when the said top unit is in normal lowered position, a side of the frame including a removable section for the application and removal of the units, and means for manually operating the units
20 to raise and lower the same and including means for locking the units in any position.
